UNITED STATES PATENT OFFICE.

FRANK L. BURDICK, OF NEBRASKA CITY, NEBRASKA.

SMOKER'S APPLIANCE.

No. 833,121.

Specification of Letters Patent.

Patented Oct. 9, 1906.

Application filed December 14, 1905. Serial No. 291,744.

To all whom it may concern:

Be it known that I, FRANK L. BURDICK, a citizen of the United States, residing at Nebraska City, in the county of Otoe and State 5 of Nebraska, have invented certain new and useful Improvements in Smokers' Appliances; and I do hereby declare the following to be a full, clear, and exact description of the invention, such as will enable others skilled in the art to which it appertains to make and use the same.

This invention relates to improvements in smokers' appliances, and while primarily designed for the purpose of a cigar-ash receiver 15 and spark-arrester may be used with other methods of smoking tobacco.

The principal object of the invention is to provide a container or casing of non-combustible material adapted to receive and contain 20 the lighted portion of the article being smoked, and thereby prevent the dropping of ashes or blowing about of sparks, the device being particularly applicable for use in windy weather or during rapid transportation in the 25 open air.

While I do not limit myself to the exact details herein disclosed, still for the purpose of more clearly understanding the invention reference is had to the following description 30 and annexed drawings, illustrating a practical embodiment of the invention, the particular features of novelty being pointed out in the appended claims.

In the drawings, Figure 1 is a view in elevation of the device shown in combination with a mouthpiece and as associated with an inclosed cigar; and Fig. 2 is a longitudinal sectional view thereof, the cigar being shown in elevation.

1 is a casing, which I term the "container," of any suitable non-combustible material, preferably formed in the shape of a cigar and freely perforated throughout its length. As stated, this casing may be made of any suitable non-combustible freely-perforated material, but is preferably formed of intermeshed or coarsely-woven wire pressed or stamped into the desired size and shape. To one end of this container or casing is attached 45 one or more spring-arms 2, provided with depressions 3, the arms 2 being adapted to be inserted in longitudinal closed slots 4, formed within the body portion of a mouthpiece 5,

so as to leave the peripheral surface unbroken, and held therein by their spring tension. 55

It will be understood that the spring-arms may be of any desired form and interlocked with the mouthpiece in any other suitable way than that just described, and, indeed, the mouth-piece may be dispensed with entirely 60 and the arms 2 by their inward spring tension brought into engagement with the end of the cigar to hold the casing in place when desired to smoke the cigar without the mouth-piece. 65

The container 1, it will be observed, affords protection to the cigar while being conveyed around in the pocket of a smoker; but it will be found desirable to provide suitable reinforcing means to prevent the casing from being buckled inwardly. Various forms of reinforcing members might be employed, and for the purpose of illustration in Figs. 1 and 2 there is shown a wire member 6 coiled around said casing in such manner as to extend longitudinally thereof, the various convolutions being soldered or otherwise secured to the container or casing. 70 75

What I claim is—

1. In a device of the character described, 80 the combination with an elongated freely-perforated casing of non-combustible material adapted to receive a cigar, of a longitudinal reinforcing member extending spirally around the exterior of said casing and associated therewith to retain the latter's shape, 85 substantially as described.

2. In a device of the character described, the combination with the freely-perforated elongated casing of non-combustible material, of a mouthpiece having an unbroken peripheral surface and provided with longitudinal internal slots, and means connecting said casing and mouthpiece, comprising spring-arms, having depressed portions and tensioned to spring outwardly, connected at one of their ends to said casing and adapted at their free ends to be inserted within said slots for interlocking said mouthpiece to said casing, substantially as described. 90 95 100

In testimony whereof I affix my signature in presence of two witnesses.

FRANK L. BURDICK.
